UNITED STATES PATENT OFFICE.

DANIEL J. GORMAN, OF PHILADELPHIA, PENNSYLVANIA.

DESIGN FOR A BEVERAGE-DISPENSER.

54,739.

Specification for Design.

Patented Mar. 23, 1920.

Application filed August 16, 1919. Serial No. 318,047. Term of patent 3½ years.

To all whom it may concern:

Be it known that I, DANIEL J. GORMAN, a citizen of the United States, and a resident of Philadelphia, county of Philadelphia, and State of Pennsylvania, have invented a certain new, original, and ornamental Design for Beverage-Dispensers, as shown in the accompanying drawings, in which the figure is a front elevation of the beverage-dispenser embodying the new design.

I claim:

The ornamental design for a beverage dispenser substantially as shown.

In witness whereof, I have hereunto set my hand this 15th day of August, A. D., 1919.

DANIEL J. GORMAN.

Witnesses:

MERRILL T. CRAMER,
J. STUART FREEMAN.
